UNITED STATES PATENT OFFICE.

GEORGE E. RANDLES, OF CLEVELAND HEIGHTS, OHIO, ASSIGNOR TO THE FOOTE-BURT COMPANY, OF CLEVELAND, OHIO, A CORPORATION OF OHIO.

MULTIPLE-SPINDLE MACHINE-TOOL.

1,396,781.

Specification of Letters Patent. Patented Nov. 15, 1921.

Application filed May 2, 1918. Serial No. 232,009.

To all whom it may concern:

Be it known that I, GEORGE E. RANDLES, a citizen of the United States, residing at Cleveland Heights, in the county of Cuyahoga and State of Ohio, have invented a certain new and useful Improvement in Multiple-Spindle Machine-Tools, of which the following is a full, clear, and exact description.

10 The object of this invention is to provide a machine which will perform certain machine operations on a large number of similar pieces of work in a given time; in other words, a machine having a large capacity 15 output.

20 The machine in which the invention is embodied is organized with a plurality of tools, a like number of work holders, a movable carrier for said tools and work holders, and means to cause such movements of the 25 tools, work holders and carrier as will cause the simultaneous operation of a plurality of tools on a like number of work pieces, and to cause each tool to perform upon the 30 work piece with which it is associated the particular machining operation the tool is adapted to perform while the carrier is going through its cycle of movement.

35 The invention consists in the construction and combination of parts shown in the drawing, hereinafter described and definitely pointed out in the appended claims.

40 In the drawings, Figure 1 is a fragmentary perspective front view of the machine; Fig. 2 is a front elevation partly in central vertical section of said machine, when certain of the tools and work holders have been taken off; Fig. 3 is a sectional plan view taken in three different planes, to-wit, the 45 right half of the view being a section in the plane of line 3-3 of Fig. 2, the lower half of the left side of said view being a section in the plane of line B-B on Fig. 2, and the upper part of the left side of the figure being a section in the plane of line A-A on Fig. 2; Fig. 4 is a plan view of the rotatable head; Fig. 5 is a plan view partly sectioned of the base of the machine.

50 Referring to the parts by reference characters, 10 represents a hollow cylindrical column which is rigidly fixed to and extends upwardly from the top member 13 of a built up hollow base 12. This column and base

constitute the fixed frame-work of the machine.

55 A head 20 which serves as a carrier for the tools and work holders to be presently described is mounted co-axially with the column 10. The carrier is in the form of a hollow drum having near its upper and lower ends the sleeves 21, 22, which rotatably embrace the column 10. There is an annular anti-friction bearing 24 interposed between the top member of the hollow base and the lower end of this carrier drum, said bearing comprising two flat rings and interposed anti-friction balls or the like and there is also an annular thrust bearing 25 near the upper end of the drum interposed 60 between the sleeve 21 and a nut 14 carried by the column 10. The sides of this carrier drum are extended above the top of the column to form an oil chamber 26 which is closed by a removable plate 27, said chamber being of larger diameter than the main 65 body of the drum so as to overhang.

70 A horizontal main shaft 30 is mounted in the hollow base 12 and extends out of the same for connection with a suitable motor. Another parallel shaft 31 is also mounted 75 in the hollow base and has a driving connection with shaft 30 through the gears 32, 39. A worm 33 is fixed to the shaft 31 and this engages a worm wheel 34 fixed to a vertical shaft 35 which extends up out of 80 the hollow base and has a pinion 36 on its upper end. This pinion is in mesh with a gear 37^a that is fixed to a shaft 37^b which carries a pinion 37 which in turn engages 85 the internal ring gear 28 which is fixed in 90 the lower end of the carrier drum. A clutch 38 of any suitable kind should preferably be provided at some place so that motion will not be transmitted from the driving shaft 30 to the carrier drum 20 unless 95 that is desired. In the construction shown a clutch 38 is provided for connecting and disconnecting the gear 39 and the shaft 30. When this clutch is thrown in the rotation 100 of shaft 30 causes the carrier drum to rotate. When this clutch is thrown out the drum will not rotate, but the other mechanism to be now explained will continue to operate.

105 On the outside of the carrier drum or head 105 a plurality of vertical rotatable spindles 40

are mounted. There may be as many of these as are desired. In the machine as shown twelve of them are provided. Each is rotatably mounted in a vertically adjustable bearing sleeve 41, which is contained in a sleeve 42 carried by the head. The bearing sleeve may be adjusted up and down by means of a rack 43 which it carries, and a pinion 44 rotatably mounted in the sleeve 42 for engagement with said rack; said pinion having a squared stem 45 which projects out of sleeve 42 to permit it to be turned. Nuts 46 which screw onto the spindle engage the ends of the sleeve 42; and therefore, as the sleeve is moved up and down, the spindle is likewise so moved. Each spindle projects into the oil chamber 26 in the upper end of the head, and has a driving connection with a pinion 48 located in said chamber. In the specific construction shown this pinion is fixed to the upper end of a sleeve 47 which is rotatably mounted in a bearing carried by the bottom of the overhanging part of the oil chamber 26, said sleeve having a flange 49 on its lower end which flange and the pinion 48, which is fixed to the upper end of sleeve 47, prevent the sleeve from moving endwise in its bearings. The spindle 40 goes through and has a tongue and groove connection with this sleeve 47.

A properly mounted vertical shaft 50 extends from the hollow base up centrally through the column 10 and it carries on its upper end a pinion 54. At its lower end it carries a bevel gear 53 which meshes with a bevel gear 30^a fixed to shaft 30. Trains of gears are interposed between the pinion 54 and the several pinions 48 on the spindles. As stated, twelve of these spindles are employed in the machine as shown, but this number is arbitrarily chosen. With that number, however, it has been found advisable to mount on vertical axes within the chamber 26 three equally spaced gears 55. Each of these gears meshes with two gears 56 which are also mounted to rotate on vertical axes, and are located within the chamber 26. Each of these gears meshes with two of the pinions 48 on adjacent spindles 40. It is evident, therefore, that as the shaft 50 rotates all of the spindles 40 will be rotated in the same direction and at the same speed regardless of whether the carrier drum or head is turning or stationary.

Associated with each spindle is a slide 60. Each slide is mounted in a vertical guide-way 39 on the outer surface of the carrier drum. Each slide has mounted in suitable bearings at its lower end a wheel 61; and all of these wheels on the twelve spindles rest upon and engage the top cam surface of a cam ring 70 which is concentric with and surrounds the lower end of the carrier drum, and is removably fixed to the base. This cam ring is made in at least two separable parts,

so that it may be easily removed and replaced by another ring having a suitable cam surface for moving the slides 60 as desired.

At what may be called the front side of the machine this cam surface has a depressed portion 71. When each slide comes above that depressed portion the slide is permitted to drop down to such a position as will cause the work which the slide carries to be disengaged from the tool which the associated spindle carries, as will be hereinafter described. To insure that this downward movement of the slide shall take place as stated, an arm 62 is fixed to each slide and it carries a roller 63 which is adapted to engage with the under face of a cam 72 secured to the cam ring 70.

In order that this machine shall be adapted to perform the functions for which it is organized, it is necessary that a suitable tool be secured to either each spindle or each associated slide, and that a work holder be provided on the other of these two parts.

In the construction shown I have chosen, to form the lower end of the spindle to receive and hold a drill,—which necessitates that the slide 60 shall be provided with a work holder. In the construction shown the work is supported upon a shelf 64 carried by the slide 60 and extended beneath the lower end of the spindle. A clamping plate 65 is arranged above this shelf and is fixed to four vertically movable rods 66 which rods are vertically movable through holes in the shelf and through holes in sleeves 67 fixed to the slide above the shelf. A spring 68 surrounds the upper projecting end of each of these rods and is compressed between the upper end of the associated sleeve and a nut 69^a fixed to the rod. A cam lever 69 is pivoted to the slide in a position to engage with the top of this clamping plate. It is evident, therefore, that in the normal operation of the machine each slide will be rigidly brought over the depressed part of the cam 70 and will be moved downward. The clamp operating cam lever associated with this slide will be swung to such position that the springs will lift the clamping plate. Thereupon a piece of work may be taken out and another piece inserted, which will be clamped in place by the reverse operation of the lever.

As the carrier drum continues to rotate to carry any slide away from the front of the machine, the roller 61 carried by this particular slide will by its engagement with the cam 70 be rather quickly lifted so as to bring the work clamped on this slide into engagement with the tool carried by the associated spindle. Thereafter while the carrier drum is rotated this slide will, by the action of the cam thereon, be slowly raised so as to move the slide and work lengthwise of the spindle, whereby the tool

carried by the spindle will perform that particular machining operation it is designed to perform upon the piece of work held by this slide, while the carrier drum is 5 going through its cycle of movement, that is to say, is completing one revolution.

It will be understood, of course, that a similar slide may be associated with each spindle, and that each slide will or may be 10 associated with substantially the same mechanism above described.

It will have been noted that certain of the operating mechanism is contained in the hollow base 12; in the drawing it will be seen 15 that substantially all of this is on one side of a vertical hollow partition 14 which extends across the base and divides the same into two chambers 15, 16. This hollow partition has a large number of holes through 20 both of its parallel vertical walls, and this hollow partition is filled with some filtering material, as for example, mineral wool. An oil pump 80 is provided for pumping oil out of the chamber 15 at the left side of the partition referred to. The oil drawn by this 25 pump is forced through a pipe 81 which extends up through the central hollow column 10 and discharges into the chamber 26, in the upper end of the carrier head, in which 30 are the numerous intermeshing gear trains before referred to. The gears in these gear trains therefore rotate in the oil contained in this chamber. There is a drain pipe 82 extending up into the chamber to the desired 35 level into which this oil will run. This drain pipe is connected with the pipe 83 which extends down through the hollow column 10 and is discharged into the oil chamber 16 in the base at the right side of 40 the partition referred to. This oil will, as before stated, go through the filtering partition into the chamber 15 at the left side thereof.

A pipe 90 is passed centrally through the 45 plate 27 into the chamber 26 at the upper end of the head, and this pipe has a swiveled connection with the supply pipe 91 above the head. This pipe extends down and discharges into an annular chamber 23 formed 50 on the head, which chamber is provided with discharge ducts one located adjacent each of the spindles 40. From some suitable points water or some other fluid if desired, flows through this pipe 90 into said annular 55 chamber 23, and is continuously discharged therefrom onto the spindles and the work pieces to keep the tool and work cold. All

of this water so discharged falls into an annular trough 95 fixed to the top member of the hollow base. A suitable drain pipe 96 60 is provided for this trough.

Having described my invention I claim:

1. In a machine tool, the combination of a drum which is rotatable upon a vertical axis and has at its upper end a hollow overhanging oil chamber, a central hollow column around which said drum rotates, a vertical shaft which extends through said column and into said oil chamber, a plurality of vertical spindles rotatably mounted on said 70 drum and projecting into said oil chamber, trains of gears in said oil chamber intermediate of said shaft and the several spindles, and means to supply oil to said oil chamber.

2. In a machine tool, the combination of a central hollow column, a drum rotatably mounted upon said column, anti-friction bearings upon which said drum is supported, thrust bearings secured to said central column and engaging the upper part of said drum, said drum being provided at its upper end with an overhanging oil chamber in which the last mentioned thrust bearings lie, a plurality of spindles rotatably mounted upon said drum and projecting upward into said oil chamber, and a central shaft which passes up through said hollow central column into the oil chamber, and trains of gears in the oil chamber intermediate of said central shaft and the several spindles.

3. In a machine tool, the combination of a tubular central column, a drum rotatably mounted thereon carrying a plurality of associated rotatable spindles and longitudinally movable work holding slides, said drum having at its upper end an overhanging hollow oil chamber, a hollow base upon which said central column is supported, an 100 oil pump in said base, a pipe leading therefrom and discharging into the said overhanging oil chamber, oil ducts in the upper end of said hollow column communicating with the hollow oil chamber, and other oil 105 ducts through the lower end of said hollow central column discharging into said base.

In testimony whereof, I hereunto affix my signature.

GEORGE E. RANDLES.
